(57) **CLAIM**

The ornamental design for a container cover, as shown and described.

DESCRIPTION

FIG. 1 is a front upper left perspective view of a container cover embodying a first embodiment of our inventive design;

FIG. 2 is a top plan view of the container cover of FIG. 1; FIG. 3 is a front elevational view of the container cover of FIG. 1;

FIG. 4 is a rear elevational view of the container cover of FIG. 1;

FIG. 5 is a right side elevational view of the container cover of FIG. 1;

FIG. 6 is a left side elevational view of the container cover of FIG. 1;
FIG. 7 is a front upper left perspective view of a container cover embodying a second embodiment of our inventive design;
FIG. 8 is a top plan view of the container cover of FIG. 7;
FIG. 9 is a front elevational view of the container cover of FIG. 7;
FIG. 10 is a rear elevational view of the container cover of FIG. 7;
FIG. 11 is a right side elevational view of the container cover of FIG. 7;
FIG. 12 is a left side elevational view of the container cover of FIG. 7;
FIG. 13 is a front upper left perspective view of a container cover embodying a third embodiment of our inventive design, with the front upper left perspective view of FIG. 13 depicting two sides of the three-sided junction in broken lines and wherein the third side of the three-sided junction would be similarly portrayed by a broken line in a rear upper right perspective view;
FIG. 14 is a top plan view of the container cover of FIG. 13;
FIG. 15 is a front elevational view of the container cover of FIG. 13;
FIG. 16 is a rear elevational view of the container cover of FIG. 13;
FIG. 17 is a right side elevational view of the container cover of FIG. 13;
FIG. 18 is a left side elevational view of the container cover of FIG. 13;
FIG. 19 is a front upper left perspective view of a container cover embodying a fourth embodiment of our inventive design, with the front upper left perspective view of FIG. 19 depicting two sides of the three-sided junction in broken lines and wherein the third side of the three-sided junction would be similarly portrayed by a broken line in a rear upper right perspective view;
FIG. 20 is a top plan view of the container cover of FIG. 19;
FIG. 21 is a front elevational view of the container cover of FIG. 19;
FIG. 22 is a rear elevational view of the container cover of FIG. 19;
FIG. 23 is a right side elevational view of the container cover of FIG. 19;
FIG. 24 is a left side elevational view of the container cover of FIG. 19;
FIG. 25 is a front upper left perspective view of a container cover embodying a fifth embodiment of our inventive design;
FIG. 26 is a top plan view of the container cover of FIG. 25;
FIG. 27 is a front elevational view of the container cover of FIG. 25;
FIG. 28 is a rear elevational view of the container cover of FIG. 25;

FIG. 29 is a right side elevational view of the container cover of FIG. 25;
FIG. 30 is a left side elevational view of the container cover of FIG. 25;
FIG. 31 is a front upper left perspective view of a container cover embodying a sixth embodiment of our inventive design;
FIG. 32 is a top plan view of the container cover of FIG. 31;
FIG. 33 is a front elevational view of the container cover of FIG. 31;
FIG. 34 is a rear elevational view of the container cover of FIG. 31;
FIG. 35 is a right side elevational view of the container cover of FIG. 31;
FIG. 36 is a left side elevational view of the container cover of FIG. 31;
FIG. 37 is a front upper left perspective view of a container cover embodying a seventh embodiment of our inventive design, with the front upper left perspective view of FIG. 37 depicting two sides of the four-sided junction in broken lines and wherein the remaining two sides of the four-sided junction would be similarly portrayed by broken lines in a rear upper right perspective view;
FIG. 38 is a top plan view of the container cover of FIG. 37;
FIG. 39 is a front elevational view of the container cover of FIG. 37;
FIG. 40 is a rear elevational view of the container cover of FIG. 37;
FIG. 41 is a right side elevational view of the container cover of FIG. 37;
FIG. 42 is a left side elevational view of the container cover of FIG. 37;
FIG. 43 is a front upper left perspective view of a container cover embodying an eighth embodiment of our inventive design, with the front left perspective view of FIG. 43 depicting two sides of the four-sided junction in broken lines and wherein the remaining two sides of the four-sided junction would be similarly portrayed by broken lines in a rear upper right perspective view;
FIG. 44 is a top plan view of the container cover of FIG. 43;
FIG. 45 is a front elevational view of the container cover of FIG. 43;
FIG. 46 is a rear elevational view of the container cover of FIG. 43;
FIG. 47 is a right side elevational view of the container cover of FIG. 43; and,
FIG. 48 is a left side elevational view of the container cover of FIG. 43.
The broken lines and unshaded areas shown in the figures are for illustrative purposes only and form no part of the claimed design.
